GLIDER STRUCTURE

William I. Smith, Goshen, Ind., assignor to The Hettrick Manufacturing Company, Toledo, Ohio, a corporation of Ohio

Application December 4, 1939, Serial No. 307,355

4 Claims. (Cl. 5—124)

This invention relates to articles of furniture but more particularly to a glider or couch equipped with a spring supporting structure on which rest the seat cushions and an object is to eliminate the usual flaps ordinarily attached to the seat cushions and which hang down over the front portion of the couch or glider for concealing the springs, and to produce a structure having a panel of metal or other suitable sheet material which extends across the front with the upper edge of the panel disposed sufficiently below the seat cushions so as to enable movement of a person with the cushioning movement of the spring structure without contact with or annoyance by the panel, which serves not only as an ornamental feature but also as a partial cover for the spring structure, the remainder of the exposed spring structure being suitably covered, as by a flexible envelope.

Other objects and advantages will hereinafter appear and for purposes of illustration but not of limitation, an embodiment of the invention is shown in the accompanying drawing in which

Figure 1 is a front perspective view of a glider, portions being broken away to show the supporting coil spring structure and associated parts;

Figure 2 is an enlarged fragmentary view in perspective of a front corner portion of the glider seat structure;

Figure 3 is a fragmentary end elevation of the front portion of the seat structure;

Figure 4 is an enlarged vertical sectional view on the line 4—4 of Figure 3; and

Figure 5 is a fragmentary end view in perspective of an alternate form of front apron panel.

The illustrated embodiment of the invention comprises a glider having a supporting frame provided with a pair of upright end panels 10 to which are connected a pair of spaced substantially U-shaped tubes 11 so arranged as to support the end panels 10 in the desired position. As will be readily understood by those skilled in this art, the glider seat structure generally indicated at 13 is suspended from the upright end panels 10 by pairs of pivotally mounted hangers 12, two being disposed at each side of the glider. The hangers 12 are pivotally connected at their lower ends to legs 14 depending from the seat frame 15. The detail construction of the seat frame 15 is not considered necessary. Suffice it to say that it includes a horizontally extending bar 16 of angle iron to the opposite ends of which are secured rearwardly extending angle iron bars 17. Secured to the frame 15 is a coil spring

structure, which is made up of a series of crisscrossing wire rods 18 suitably carrying vertical coil springs 19 generally helical in shape but which taper from top to bottom, the smaller portion being disposed at the lower end. It will be understood that a similar crisscrossing system of wire rods is disposed at the upper ends of the springs and a border wire 20 extends entirely around the spring structure.

A suitable back frame (not shown) connects to the rear end of the seat frame 15 and resting thereagainst are cushions 21. Likewise resting upon the supporting spring structure are cushions 22, which may be of any suitable type. Ordinarily the seat cushions 22 are provided with flaps 15 at the front end and these flaps hang down to cover the front portion of the glider, obscuring the spring structure and the supporting frame. These flaps have been found to be unsatisfactory inasmuch as they become wrinkled and unsightly after a period of time and also because they militate against shifting of the seat cushions to different positions, rendering it impossible completely to reverse the cushions so that the front edge portions are at the rear of the glider. In accordance with this invention, the use of flaps is eliminated and, as shown, a panel 23 of light gauge sheet metal or other suitable material extends entirely across the front of the glider, approximately one-half of the width of the panel 30 extending above the front cross bar 16 and the other half below the bar 16. As shown, the panel inclines upwardly and rearwardly above the cross bar 16 and downwardly and rearwardly below the cross bar 16. In this instance the panel 23 is longitudinally fluted for ornamental purposes. It will also be noted that the upper edge portion 24 is beaded or rolled over a rod 25 the ends of which project beyond the ends of the panel and such projecting end portions are screw-threaded. The panel 23 covers approximately one-half of the space between the top and bottom of the coil spring structure, leaving a space between the upper edge of the panel and the seat cushions 22. This arrangement is of importance because it enables a person to sit upon the seat cushions and compress the coil spring structure without troublesome interference by the upper edge of the panel. It is apparent that in the event that the metal panel 23 extended to the top of the coil spring structure that the top edge would present an unyielding surface which would be most uncomfortable to a person sitting on the glider in the usual manner.

As shown, a flap or wing 26 at opposite ends of

the panel is integral with the lower portion thereof and extends at substantially right angles thereto. The flaps 26 overlap the adjacent side bars 17 respectively. Extending outwardly from each side bar 17 is a headed pin 27, which extends through an opening in the flap 26. The screw threaded projecting ends of the rod 25 extend through openings in side panels 28 which are formed with arm rest 29 at the upper ends. 5 A nut 30 is connected to each end of the rod 25 and clamps the panel 23 and adjacent panel 28 together. A screw 31 connects each flap 26 to the adjacent bar 17 and screws 32 connect the panel 23 to the cross bar 16. Each of the arm rest carrying panels 28 are provided with vertical braces 33 which are suitably secured in place and have notches 34 at their lower ends to slip over the headed pin 27. A headed pin 34 on the inner side of each brace 33 is adapted to engage in an 10 inclined slot 35 which is formed on a bracket 36 suitably secured, as by welding, to the front end portion of each of the bars 17.

In order to cover the exposed portion of the coil spring structure between the upper end of 25 the panel 23 and the seat cushions 22, a flexible cloth-like fabric covering or envelope 37 having a vertical portion 38 and a horizontal portion 39 is provided. The covering 37 only covers the front end portion of the coil spring structure and a 30 portion of the opposite ends. The envelope 37 is sufficient to cover the remaining exposed portion of the coil spring structure and affords the additional purpose of protecting persons sitting on the seat cushions from contact with the coil 35 springs and associated structure.

In order to hold the flexible covering 37 sufficiently taut and for retaining it in place so that it will not creep over the upper edge portion of the panel 23, a flexible strap 40 is secured, as by 40 sewing, to the under side of the vertical portion 38 of the cover. Attached to the lower end of the strap 40 is a hook member 41 which engages the lower edge portion of the angle iron cross bar 16. Preferably a number of these hook members are employed at spaced intervals in 45 order to properly retain the cover in the desired position.

In the alternate form shown on Figure 5, the panel 23a has an integral end flap 42 which overlaps the arm rest carrying panel 28a. The end portion 42 extends at substantially right angles to the panel 23a and is substantially co-extensive therewith, the lower portion 43 inclining upwardly and rearwardly as shown. A single screw 44 may secure the end portion to the panel 55 28a.

From the above description, it will be apparent that this structure not only enables the seat cushions 22 to be used in any desired manner so that they can be reversed or interchanged as desired, but also provides a more comfortable structure. The panel 23 is shaped for the greatest comfort and is so positioned as to be free from being a nuisance to the occupant of the glider when in a normal sitting posture, the intermediate spring covering being of real im-

portance in protecting the occupant from the coil spring structure, as well as enhancing the appearance of the assembly.

It is to be understood that numerous changes in details of construction, arrangement and operation may be effected without departing from the spirit of the invention especially as defined in the appended claims.

What I claim is:

1. An article of furniture comprising a seat 10 frame, a spring supporting structure on said seat frame, seat cushions loosely resting on said spring supporting structure, a panel of sheet material extending across the front of said frame with its upper edge disposed intermediate the top and 15 bottom of said spring supporting structure, the lower portion of said panel inclining downwardly and rearwardly, and a covering for the portion of said spring supporting structure exposed between the upper edge of said panel and said 20 cushions, whereby the front portion of said spring supporting structure may be substantially compressed by a person sitting on same without engagement with the top edge of said panel.

2. An article of furniture comprising a seat 25 frame, a spring supporting structure on said seat frame, seat cushions on said spring supporting structure, a panel of sheet material extending across the front of said frame with its upper edge disposed intermediate the top and 30 bottom of said spring supporting structure, rearwardly extending wings on opposite ends of said panel overlapping and concealing the front ends of said seat frame, and a covering for the portion of said spring supporting structure exposed 35 between the upper edge of said panel and said cushions, whereby the front portion of said spring supporting structure may be substantially compressed by a person sitting on same without engagement with the top edge of said panel.

3. A glider comprising a seat frame mounted for to and fro swinging movement between laterally spaced upright interconnected end frames, said frame including front and side bars, a spring supporting structure, seat cushions loosely resting upon said spring supporting structure, a sheet metal panel extending across the front of said frame with its upper edge terminating approximately midway between the top and bottom of said spring supporting structure, the upper portion of said panel inclining upwardly and rearwardly and the lower portion of said panel inclining downwardly and rearwardly, rearwardly extending wings on opposite ends of said panel overlapping the adjacent ends of said seat 50 frame, a flexible cloth-like envelope covering the portion of the spring supporting structure exposed between the panel and cushions, and hooks flexibly connected to the lower portion of said envelope and engaging said front bar for holding 55 said envelope in place relative to said panel.

4. An article of furniture in accordance with claim 2, wherein the lower portion of the panel inclines downwardly and rearwardly.

WILLIAM I. SMITH.
